DESCRIPTION

U.S. PATENT DOCUMENTS

238,117 A	2/1881	Hillman
600,879 A	3/1898	Louden
1,457,770 A	6/1923	Dodge
1,465,691 A	8/1923	Snedeker
1,623,547 A	4/1927	Neumann
1,865,688 A	7/1932	Hannaford
1,897,672 A	2/1933	Neumann
1,974,674 A	9/1934	Halladay et al.
2,019,371 A	10/1935	Tompkins
2,054,355 A	9/1936	Anderson, Jr.
2,094,054 A	9/1937	Bixby

FIG. 1 is a perspective view of the new design;
FIG. 2 is a side view of the new design;
FIG. 3 is an end view of the new design;
FIG. 4 is another end view of the new design;
FIG. 5 is a top view of the new design; and,
FIG. 6 is a bottom view of the new design.
The broken lines shown in the drawings depict environmental features that form no part of the claimed design.

1 Claim, 5 Drawing Sheets# US D712,251 S
